UNITED STATES PATENT OFFICE.

CHARLES L. GOEHRING, OF ALLEGHENY, PENNSYLVANIA.

MOLDING-MACHINE.

SPECIFICATION forming part of Letters Patent No. 394,763, dated December 18, 1888.

Application filed January 7, 1888. Serial No. 260,097. (No model.)

To all whom it may concern:

Be it known that I, CHARLES L. GOEHRING, of Allegheny, in the county of Allegheny and State of Pennsylvania, have invented certain new and useful Improvements in Molding-Machines; and I do hereby declare the following to be a full, clear, and exact description of the same, reference being had to the accompanying drawings, forming a part of this specification, and to the figures and letters of reference marked thereon.

This invention relates to a new and improved system comprising a series of separate co-operating mechanisms for the production of ornamental and other designs, figures, or moldings in or upon the surface of wood or other materials by the action thereon of revolving cutters or abrading-instruments, and in which the material operated upon is moved or advanced constantly in one direction, while the cutters are automatically shifted or adjusted laterally with respect to the line of movement of the material to vary the direction of the cut; and the said invention comprises as its principal but not its only element of novelty and invention the combination and employment, in an organized machine, of, first, a mechanism or devices competent to feed or advance the material to be operated upon; second, one or more cutting or abrading devices located in the line of travel of the material and adapted to operate thereon as it is fed or moved forward; third, adjusting devices competent to effect and control the application of each of said cutting devices and to shift and vary its position relatively to the line of feed or movement of the material to be operated upon, and, fourth, actuating devices moving in unison with the feeding mechanism and operating to control the movements of the adjusting devices, whereby the movement or adjustment of each cutter to vary and control the line of cut, and thereby the configuration or form of the elements entering into and constituting the design, is controlled by and made dependent upon the rate of feed or movement of the material upon which said cutters operate.

In the accompanying drawings, wherein I have shown a form and construction of mechanism illustrating the principle and its application, Figure 1 is a top plan view of an or-

ganized machine containing my improvements. Fig. 2 is a side elevation, and Fig. 3 a longitudinal vertical section, of the machine, Fig. 1. Figs. 4, 5, and 6 are transverse vertical sections on lines $x\acute{x}$, $y\acute{y}$, and $z\acute{z}$, respectively, of Fig. 1. Fig. 7 is a longitudinal vertical section through one of the cutting mechanisms. Fig. 8 illustrates in plan and section a few of the innumerable designs which may be formed by the machine shown. Figs. 9, 10, and 11 are diagrammatic views illustrating the action of the cutters.

Similar letters of reference in the several figures indicate the same parts.

In illustration of the composition and adaptation of my improved system, the four constituent elements thereof—viz., the feeding, the cutting, the adjusting, and the actuating or regulating devices or mechanisms—are represented, the first by rolls A, of which two or more pairs are preferably employed, being driven at equal peripheral velocities, so that the material—such as a board—when inserted between the members of the first pair of rolls A, will be grasped and carried or fed forward at a rate dependent wholly upon the speed of the rolls; the second by one or more rotating cutter-heads or sets of cutter-heads, B B' B², each furnished with cutters or bits of appropriate form; the third by the mechanism or carriages and movable slides connected to or carrying the supports for each cutter-head, the whole constituting an adjusting system by which the requisite movements of the cutter-heads relatively to the line of feed are obtained, and the fourth by a system of gearing or driving mechanism uniting the adjusting system and feeding devices A together or to the prime motor, so that the movements of each shall have a fixed and determinate relation to the other. Now the primary object and result of this arrangement of co-operative elements is the establishment and maintenance of the uniform movement or adjustment of each cutter-head relatively and proportionally to each other and to the progressive movement or feed of the material, so that by varying the proportions in or throughout the gearing the excursions of the cutter-heads may be increased or diminished, the rate of speed being constant, or vice versa. The value and importance of

this feature, especially in its application to adjusting devices of the character shown, will hereinafter appear.

Turning now to the special application of the principle shown in the drawings, it will be seen that the several mechanisms and devices are appropriately supported and mounted upon a substantial frame-work, E, in order that the various devices may be maintained at all times securely in their relative positions.

The upper rolls, a, of each pair of feed-rolls A are supported in vertically adjustable and movable bearings a', held down by the yielding pressure of weights a². The bearings a' are connected by rods m with a cross-head, m', and to the weight a² by rods m². The cross-head m' is held in adjusted position by a screw, m³, engaging a threaded aperture therein, and provided with a collar, or shoulder, m⁴, resting in contact with the top of the housings. Both rolls of each pair are preferably made of the same diameter, and all the said rolls are connected by gearing in the usual manner, as shown, so that all of the feed-rolls will be rotated at the same speed, or so as to have equal peripheral velocities. These forms or varieties of cutting mechanisms (designated B, B', and B²) are illustrated, any one or more of which may be employed or thrown out of operation, as desired, to adapt the machine to the particular pattern or design to be produced, and in addition to these I have included as accessories two roughening or finishing cutters, B³ B⁴.

Although, as is obvious, the relative position and arrangement of the several cutting mechanisms may be varied, if desired, without departing from the spirit of my invention, I will hereinafter describe and refer to them in the order and arrangement in which they are illustrated in the drawings.

The first cutting mechanism, B, of the series is located between the two sets of feed-rolls and comprises a pair of cutter-heads, b, supported on vertical arbors b', and designed to give form to the edges or sides of the article as it passes between them. The cutters or bits are of appropriate form—for example, one being adapted to form a groove and dress one edge of the plank and the other to form a tenon and dress the opposite edge, while the arbors carrying said cutter-heads are so arranged and supported as that they may be reciprocated toward and from each other on the line of feed; whereby the edges of the plank may be given either a regular or irregular outline, as will presently appear.

The arbor b' of each cutter-head b, provided with a pulley or other appropriate driving-gear, is supported in bearings b² on the overhanging arm b³ of a slide, b⁴, the latter held and supported in ways on the frame, and said slide b⁴ carries an abutment or anti-friction wheel, b⁵, held in contact with an eccentric or cam, C', of appropriate outline, by a weight

and chain or cord or other equivalent yielding connection, such as will operate to hold the slide retracted with a yielding pressure 70 against the face of its pattern-cam C'.

In order to provide for the ready adaptation and adjustment of the machine to operate upon different widths of material, the said sliding frame b⁴ is constructed in two sections, 75 the one carrying the arm b³ sliding longitudinally in ways in the base, the two parts being united by an adjustable connection—such as a screw, b⁶, threaded through a lug on the base and provided with collars engaging a lug, b⁷, on the upright; or, as preferred, a rack, b⁸, may be secured to the upright and a gear, b⁹, supported in bearings on the base, said gear meshing with the rack and connected through suitable gearing with a hand-wheel 85 or lever at or near the front of the machine, so that the operator can readily and quickly effect the lateral adjustment of the arbor and its cutter-head.

Beyond the second set of rolls is located 90 the first or top dressing cutter, B³, comprising a cutter-head, b, standing parallel with and above the table and secured to an arbor, c, rotating in bearings c', carried by a longitudinally-movable slide or carriage, c², the latter carrying an abutment or roller, b⁵, held in contact with an eccentric or pattern cam, C², by a yielding pressure device—such as a weight—connected to a cord or chain passing over a pulley on the frame and attached at 100 one end to said slide c².

For the purpose of accommodating the cutter to different thicknesses of material, the slide c², instead of being supported directly upon or in the frame E, is fitted to guides in 105 a carriage, c⁴, the latter being supported in ways in the frame and moved vertically for adjustment by a screw-connection, c⁵.

The primary function of the cutter B³ is to dress off the upper face of the board; but in 110 order that it may be utilized as a roughing-tool to assist the other cutters it is arranged to be given a longitudinal reciprocating movement by the pattern-cam C². Otherwise this cam might be dispensed with and the slide 115 fastened to or made integral with the vertically-adjustable carriage c⁴. A construction of this kind is adapted for the cutter B⁴, located in the present instance at the rear end 120 of the machine and below the table, said cutter being designed for finishing the under surface of the plank.

Next in order is the cutting device B', consisting of a cutter-head, b, secured to the lower 125 end of a vertical arbor, d, the latter supported in overhanging bearings d'. The bearings or arms d' are so arranged and mounted as to permit of vertical adjustment as well as vertical and lateral movements corresponding to or following the designs of pattern-cams. Thus 130 in the illustrated machine the bearings d' are secured to a slide, d², movable in ways on a carriage, d³, the latter being supported in guides in the frame E and adapted to move

in a vertical direction. The carriage d^3 is made in two sections, the one d^4 carrying the ways for the slide d^2 , and the other, the roller, resting upon the pattern-cams C^3 . Said sections, sliding the one in or upon guides formed on the other, are united by an adjustable connection—such as the screw d^5 —whereby the position of the cutter is adjusted and determined.

10 The slide d^2 is provided with an abutment or roller-bearing, b^5 , held in contact with its cam C^4 by yielding connection—such as a weight, as indicated by dotted lines, Fig. 6.

15 The number of cutting mechanisms B' to be employed depends largely upon the form and intricacy of the design to be traced. In the present instance two such mechanisms are illustrated, situated on opposite sides of the machine, the second cutter being located just 20 in front of the finishing-cutter B' .

Beyond the vertical cutters B' , and on opposite sides of the frame, are arranged a pair of cutting mechanisms, B^2 , the one standing in advance of the other, so that both cutter-heads b will project equally over the material 25 to be operated upon.

Each mechanism B^2 (forming the subject of a separate application, No. 260,098, to which reference is made for a more full and detailed 30 description) comprises a cutter-head, b , secured to a horizontal arbor, b' , and supported in bearings on a frame or carriage, the construction and arrangement being such that the cutter-head may be moved vertically, 35 transversely, or angularly with respect to the line of feed of the material operated upon, said movements taking place simultaneously or successively and being governed or controlled by pattern-cams, as will presently be 40 explained. To effect these movements and provide for the necessary initial adjustment of the cutter-head, the arbor to which it is secured is mounted in bearings in a frame or plate, e , that is pivotally secured to a bolt, e^2 , 45 depending from the forward or overhanging end of a slide, e' , the rear end or portion of said plate e being supported in guides on the slide e' .

The rear end of the slide e' carries an abutment or roller-bearing, b^5 , held by a weight or other yielding connection in contact with the pattern-cam C^5 , and the plate e is made adjustable upon the pivot or bolt e^2 , to provide for the longitudinal adjustment of the arbor, in order that the cutter-head or cutters 55 may be placed centrally beneath the pivoted point or center of oscillation.

The angular or oscillating movement of the plate e is effected and controlled by a pattern-cam—it may be, and preferably is, the same that operates the slide e' —acting upon one arm of a bell-crank lever, e^3 , the other arm making contact with the plate e in rear of the pivot e^2 , said plate e being held against the arm of the lever by a weight or other yielding connection. Provision is thus made 65 for the longitudinal adjustment of the arbor

and the pivotal attachment of the plate carrying said arbor at a point above the work and centrally of the face of the cutters, as 70 well as for moving said cutters across the line of feed of the material, and at the same time changing or varying the angular position, so that the cutters will at all times face the material in a line substantially at right angles 75 to the direction of the cut, which latter is a matter of no inconsiderable importance, for otherwise it would be practically impossible to form the great variety of designs the machine is designed and competent to execute. 80

The path traversed by the arbor is determined by and represents the mean of two motions communicated to its support, the one motion being in a direction transverse to the line of feed—that is to say, a movement longitudinal of the arbor and across the face of the material at an angle to the forward or feeding motion of the latter—while the other movement is one tending to change or vary the angular position of the arbor relatively to 90 the movement of the material, and is effected by causing the arbor-frame to oscillate about an axis which, if prolonged, would intersect the cutters and the material. This change in the angular position of the cutter-head relatively to the direction of movement of the material passing beneath it is effected while the support for the arbor-frame is reciprocating across the material—that is to say, 95 while reciprocating in a plane transverse to the line of feed. Consequently a given point on the cutter-head would be caused to traverse a path or line on the face of the material representing the sum of the three motions, two performed by the cutter and the 100 third by the material. These movements and adjustments are sufficient if flat designs only 105 are to be produced—that is to say, figures in which the cuts or lines produced at this point are of uniform depth; but in order greatly to 110 enlarge the capacity of the machine and produce designs in an infinite variety provision is made for effecting a vertical movement or reciprocation of the cutter, said movement 115 being likewise controlled and effected by pattern-cams. To this end the slide e' , with the plate e pivotally supported thereon, is mounted in ways on a frame, e^5 , arranged to move vertically in ways in the frame E , said frame e^5 (constructed in two sections and connected by an adjusting-screw, e^6 , or equivalent device) resting upon and held by its 120 weight in contact with pattern-cams C^6 .

It is desirable that at least two of these cutting mechanisms B^2 , with the adjusting or actuating devices therefor, should be employed, and so located and arranged as to operate upon opposite sides of the face of the board when passing beneath them, in order that figures or designs may be formed by the separate 125 as well as by coincident cuts produced by the separate cutters.

In Fig. 7 I have indicated an arrangement of driving-pulleys such as may be employed

to accommodate the movements imparted to the cutter-heads and their arbors. The system of gearing is shown in connection with mechanism B², because the latter exhibits the more complex movements.

Let p represent a yoke or frame located above the arbor b'; and movable in suitable guides, p'; p², a shaft supported in frame p parallel with the movement of slide e'; p³, a wide parallel-face pulley in line with the crown-pulley p⁴ on arbor b'; p⁵, a belt encircling pulleys p³ and p⁴; p⁶, a smaller pulley on shaft p², driven by a belt from a larger driving-pulley (shown in dotted lines) supported in about the same horizontal plane as shaft p²; and p⁷, a lever connected to frame p, fulcrumed at p⁸, and carrying a weight, p⁹. As the slide e' reciprocates, the belt p⁵ is shifted along the face of pulley p³, being prevented from slipping from pulley p⁴ by the crowned or convex face of the latter. The vertical as well as radial or oscillating motions of the arbor are provided for by the counter-weight acting upon the movable frame, carrying pulley p³, and tending to hold the latter elevated against the belt, but permitting the pulley and its supports to move down to accommodate the various movements of the arbor b'.

I wish it to be distinctly understood that I do not in this application claim a special form of driving mechanism for the cutters herein shown, nor does it form part of my present invention, as any suitable combinations or arrangement of devices may be substituted or used for the purpose, as will readily be understood by any person skilled in the art.

Having described three of the four principal elements of the improved machine—viz., the feeding, cutting, and adjusting or controlling devices—the actuating mechanism alone remains. This comprises a system of gearing uniting and connecting the several pattern-cams C', C², C³, C⁴, and C⁵ and the feeding devices or rolls with the prime motor or driving-shaft, so that the whole system will move in harmony, for it is of the utmost importance that the various movements of each cutter should be accurately timed, both as to each other and to the progressive movement or feed of the material.

Any appropriate system of gearing or driving mechanism which will insure the desired unitary action of all the devices may be employed; but, by preference, it should be so organized as to permit of ready adjustment in order that the pattern-cams may be removed and others substituted, and the gearing so modified, as by the substitution of wheels or gears differing in size or dimensions, that the speed of each adjusting mechanism may be varied relatively to that of the feeding devices. An arrangement of gearing suitable for the purpose is illustrated in the drawings, wherein G' represents the main driving-shaft,

from whence motion is communicated to the feed-rolls through a train of gears, G².

Supported in bearings on the sides of the frame are three corresponding series of vertical shafts, g g' g², the first set, g, carrying the cams C', the second set, g', the cams C⁴, and the third set, g², the cams C⁵, an additional shaft, g³, being provided for cam C². The shafts g' g² of each series are driven through bevel-gears g⁴ from a shaft, G³, mounted in bearings on the side of the frame. The cams C³, controlling the vertical movements of cutting mechanism B', are secured to a shaft, g⁵, deriving motion from shaft G³ through bevel-gears g⁶ and a short shaft, g⁷, while the cams C⁶, controlling the vertical movements of cutting mechanism B², are secured to a shaft, g⁸, driven through bevel-gears g⁹ from the shaft g². The two parallel shafts G³ are connected through bevel-gears g¹⁰ with the vertical shafts g, and the latter in turn are connected together to rotate in unison by bevel-gears g¹¹ and a cross-shaft, G⁴. This cross-shaft G⁴ unites the two series of shafts controlling the movements of the several cutting mechanisms, and it is in turn connected through suitable gearing, G⁵, with the main driving-shaft G', which controls the speed of the feeding-rolls. It will thus be seen that all the movements of the several elements constituting the system are controlled directly by the main driving-shaft, and that each separate cam or series of cams will be driven in unison with the feed-roll, the speed of each cam being determined by the relative dimensions of the several gears and in direct proportion to the speed at which the material is advanced or fed toward the cutters.

With a machine constructed and working in accordance with the principles herein described and illustrated an endless variety of designs can be produced by the interchanging or substitution of gearings, by changing the form or dimensions of the cutters, by the substitution of pattern-cams of different dimensions and configuration, or by any adjustment of the several co-operative parts such as will effect a change in the time, form, and extent of the various movements given to the cutting mechanisms relatively to each other and to the feeding devices. When, however, the adjustments have once been made and the machine is set in motion, it will reproduce continuously the same designs so long as the unitary adjustment of parts remains undisturbed.

In Fig. 8 I have illustrated several of the infinite number of designs which may be formed by proper adjustment of the mechanisms in accordance with the scheme of this invention. No. 1 represents a design made up of separate boards connected by tongue-and-groove joint, each board bearing the same design upon its surface and a continuous overlapping bead on its curved edge covering the joint. In No. 2 the design on the

face of the boards is the same; but the edges are made straight instead of with interlocking curves, as in No. 1. No. 3 represents a design in which the lines are cut below the general level of the surface, as distinguished from Nos. 1 and 2, wherein the lines and figures are in relief. In No. 4 the lines and figures are formed partly above and partly below the general surface. No. 5 represents a composite design including three boards, each formed with correspondingly curved edges but different faces.

As is obvious, one or both edges can be made straight, curved, or of any desired irregular form either for the whole or a portion of their length by the proper adjustment of one or both cutting mechanisms B, and the figures on the face can also be changed or varied by the adjustment and action of cutting mechanisms B' B², and any two boards having corresponding edges can be associated together (without reference to the particular design of their surfaces) and united by a tongue-and-groove joint.

For the purpose of showing the co-operative relation of the several cutting mechanisms, I have illustrated diagrammatically in Figs. 9, 10, and 11 two sets of cutters belonging to the mechanisms B B² of the series and designed to form one of the ornamental moldings No. 5 of Fig. 8.

Fig. 9 contains a front and top views of the two cutter-heads b of the mechanism B, the arrows indicating the lines in which the arbors are moved by the controlling-cam—that is to say, simultaneously and equally in opposite directions and at a speed proportioned to the progressive movement of the plank, such as will produce the figure f. The bits or cutters t on one of the heads form a tongue, t', at the same time giving a curved form to the edge of the board by reason of the lateral movement imparted by the cam and the progressive movement of the board controlled by the feeding devices. The bits or cutters t² on the opposite but correspondingly-reciprocating head b form the opposite edge, a portion of the overlapping bead t³, and the groove t⁴.

Fig. 10 is a side and end view representing the form of bits and direction of movement of one of the cutter-heads b belonging to the mechanism B² of the series, while Fig. 11 contains similar views representing the other cutter-head of the pair. These cutter-heads are arranged to be given three motions in addition to that of rotation about the axis of the arbor—that is to say, the two cutter-heads are moved vertically and laterally and swung radially about the pivotal point of support. The vertical motion referred to is a motion of the cutter-head toward and from the face of the material in a plane intersecting the line of feed or movement. The lateral motion is one transverse to the line of feed—that is to say, across the face of the material at an angle to the line of feed—and the swinging or angular

movement is one about an axis or center of oscillation intersecting the cutter and material, whereby the angle formed at the point 70 where the axis of the cutter-head intersects the line of feed—i.e., the line of movement of the material—is varied or changed, so as to cause the cutters or bits to face the material in the line of movement represented by the 75 resultant of the three motions—viz., feed of material, transverse reciprocation of cutter-head, and oscillation or change in angular position of cutter-head. The bits t⁵ on the cutter-head, Fig. 10, are, for convenience of description, divided into three sections—the first, s, for completing the bead t³ and surface s³, the second, s', for forming the bead s⁴, and the third, s², for forming one-half of the bead or projection s⁵. The longitudinal motion of 80 the arbor—that is to say, its movement across the face of the plank—corresponds with the lateral movement imparted to the cutter-head of mechanism B', resulting in the formation of a half-molding, as shown at n.

The cutters or bits on the opposite head, Fig. 11, are duplicates of the bits t⁵, omitting section s and continuing section s' to the edge, and the movements given to the arbor are the same as are given to the one previously described, resulting in the production of a finished design or molding, r.

If the cutter-head is reciprocated vertically, the design will be correspondingly varied, as will readily be understood.

It is of course understood that suitable guides and presser-bars, P, of suitable form and construction, are to be employed. In order to adapt the machine to work upon timber of various forms in cross-section, I construct the bed E' of the machine with a longitudinal V-shaped groove or way and form the lower rolls of the feeding mechanism with corresponding grooves or depressions.

When working on material which is flat on the under surface, a filling-piece, E², is inserted and secured within the groove in E', and the grooves in the feed-rolls are also filled in with detachable sections E⁴. These removable and interchangeable filling-pieces have their upper or outer faces flush with the general surface of the table, or they may be made of any desired cross-section to receive and guide the material to be operated upon.

The method of producing figures and designs on the surface of wood and other materials referred to herein and to which this invention relates is claimed in another application, Serial No. 282,590.

Having thus described my invention, what I claim as new is—

1. In a mechanism such as described, the combination, with the feeding mechanism, of a cutting mechanism comprising an arbor carrying a cutter-head projecting across the material, bearings supporting said arbor and permitting both longitudinal and angular or lateral movements of the cutter-head in a plane parallel with the face of the material

and transverse to the line of feed, pattern-cams controlling said longitudinal and lateral movements of the cutter-head, and a gear-train uniting the feeding mechanism and pattern-cams, substantially as described.

2. In a mechanism such as described, the combination, with feeding mechanism for advancing the material continuously in the same direction, of a cutting-mechanism comprising a cutter-head and arbor mounted in bearings and moved by a pattern-cam to reciprocate the cutter-head in a plane transverse to but intersecting the line of feed to form one edge or side of the material, and a second or top dressing cutting mechanism comprising a cutter-head and arbor mounted in bearings and reciprocated simultaneously in two directions, the one transversely to the line of feed and the other longitudinally thereof by a pattern cam or cams, substantially as described.

3. In a mechanism such as described, the combination, with feeding mechanism for advancing the material continuously in the same direction, of a cutting mechanism comprising a cutter-head and arbor mounted in bearings and operated upon by a pattern-cam to reciprocate the cutter-head in a plane transverse to but intersecting the line of feed of the material, a second cutting mechanism comprising a cutter-head mounted on an arbor overlying the face of the material, supported in bearings and reciprocated by a pattern cam or cams simultaneously in two directions, the one transversely of the moving material and the other longitudinally thereof, and gearing uniting the cams of the two cutting mechanisms and the feeding mechanism, substantially as described.

4. In a mechanism such as described, the combination of the feeding mechanism operating to advance the material continuously in the same direction, a cutting mechanism comprising two cutter-heads mounted upon arbors and supported in movable bearings, the cutter-heads being located on opposite sides of the line in which the material is moved by the feeding mechanism, and the bearings operated upon by pattern-cams to cause the cutter-heads to reciprocate toward and from the opposite faces of the material as it is moved between them, and a second cutting mechanism for dressing or ornamenting the face of the material, the same comprising two cutter-heads mounted upon arbors and projected from opposite sides over the material, each of said arbors being mounted in separate bearings controlled by pattern-cams, the latter operating to reciprocate the cutter-head across the face of the material, and at the same time oscillate it so as to present the bits squarely to the line of cut, substantially as described.

5. In a mechanism such as described, and in combination with a feeding mechanism for positively advancing the material, two sets of cutting mechanism co-operating and united

through gearing with the feeding mechanism to simultaneously shape or give form to the edges or sides and the face of the material, one of said cutting mechanisms comprising two cutter-heads located on opposite sides of the path traversed by the material and reciprocated by pattern-cams and the other cutting mechanism comprising two cutter-heads arranged in succession, mounted on arbors, and overlying the face of the material, both of said arbors and cutter-heads being simultaneously reciprocated and oscillated by pattern-cams, substantially as described.

6. In a mechanism such as described, the combination, with the feeding mechanism for positively advancing the material, of a cutting mechanism co-operating and united through gearing with the feeding mechanism to produce upon the surface of the material various ornamental and other designs, said cutting mechanism comprising a cutter-head attached to a rotating arbor projecting laterally across the face of the material and mounted in movable bearings, and pattern-cams driven in unison with the feeding mechanism and operating to reciprocate said arbor and cutter-head toward and from the material as well as laterally across the face of the latter, substantially as and for the purpose specified.

7. In a mechanism such as described, the combination, with feeding-rolls for positively advancing the material in a straight line, of an oscillating reciprocating arbor supported in movable bearings and carrying a cutter-head projected across the face of the material, and pattern-cams driven in unison with the feeding mechanism controlling the oscillatory reciprocating movements of the cutter-head, substantially as and for the purpose set forth.

8. In a mechanism such as described, and in combination with the feeding mechanism for positively advancing the material, a cutter-head and arbor projected transversely across the face of the material and supported in a frame pivotally connected to a reciprocating support on an axis intersecting the material, and pattern-cams driven in unison with the feeding mechanism and operating to reciprocate said support and oscillate the arbor-frame as the material is fed past the cutters, substantially as and for the purpose specified.

9. In a mechanism such as described, the combination, with the feeding-rolls, of the cutting mechanism B', with its cutter-heads located on opposite sides of the material and affixed to parallel arbors supported in slides and actuated by pattern-cams, the cutting mechanism B², with its cutter-head mounted upon an arbor whose axis of rotation intersects the plane in which the material is fed, said arbor being supported in movable bearings actuated by pattern-cams, and a system of gearing connecting the pattern-cams and feeding-rolls to cause them to operate in unison, substantially as described.

10. In a mechanism such as described, the

combination, with the feeding mechanism for positively advancing the material, of a rotating arbor carrying a cutter-head parallel to the edge or side of the material and reciprocated by a cam in a direction transverse to the line of movement of the material, a second cutter-head projected across the face of the material and mounted upon an oscillatory reciprocating arbor whose movements 5 are controlled by a pattern cam or cams, a third cutter-head attached to an arbor whose axis intersects the material at an angle to the line of movement, said arbor being mounted in a reciprocating slide controlled by a cam 10 or cams, and a system of gearing uniting all of said cams and the driving mechanism, as 15 and for the purpose set forth.

11. In a mechanism such as described, and in combination with devices for feeding the material positively and at a predetermined 20 speed, two oscillatory reciprocating cutter-heads arranged in succession and projected and working in planes above the moving material to form distinct sections or parts of a

unitary design, the actuating devices for reciprocating and oscillating said cutter-heads being connected and driven in unison to maintain the proper relations of the sections formed by the separate cutting mechanisms and preserve the design evolved in its integrity. 25

12. In a machine or system such as described, the combination, with the feeding mechanism, of a cutter-head mounted upon the end of an arbor, which latter is supported in bearings so that its axis will intersect the 30 material, a frame supporting said bearings movable both laterally and longitudinally of the arbor and transversely to the direction in which the material is advanced, pattern-cams controlling the movements of said support, 35 and gearing connecting said cams and the feeding mechanism, as and for the purpose set forth. 40
